[57] **CLAIM**

The ornamental design for a set of front curved cleats for an athletic shoe, as shown and described.

DESCRIPTION

FIG. 1 is a front perspective view of set of front curved cleats for an athletic shoe in accordance with the invention;

FIG. 2 is a top plan view thereof;

FIG. 3 is a front view thereof;

FIG. 4 is a left view thereof;

FIG. 5 is a rear view thereof;

FIG. 6 is a right view thereof; and,

FIG. 7 is a rear perspective view thereof.

The side walls of the cleats that circumferentially face each other are flat.

The broken line showing of part of a shoe plate in FIGS. 1-7 is for illustrative purposes only and forms no part of the claimed design, the broken lines immediately adjacent the shaded areas that define the boundaries of the claimed design in FIGS. 1, 2 and 7 form no part thereof.
